ATTORNEY

UNITED STATES PATENT OFFICE.

CALVIN S. BALL, OF SYRACUSE, NEW YORK.

EYEGLASS-HOLDER.

SPECIFICATION forming part of Letters Patent No. 376,847, dated January 24, 1888.

Application filed March 11, 1887. Serial No. 230,547. (No model.)

To all whom it may concern:

Be it known that I, CALVIN S. BALL, of Syracuse, in the county of Onondaga, in the State of New York, a citizen of the United States, 5 have invented certain new and useful Improvements in Eyeglass-Holders, of which the following is a specification, reference being had to the accompanying drawings.

The object of my invention is to improve the 10 construction, the utility, and durability of eyeglass-holders, and for other purposes; and it consists in improving the construction of the hook portion by doubling it back upon itself, so that the two parts thereof are substantially 15 parallel with each other for a portion of their whole length, one of them lying close to the body of the holder, and thereby, in the first place, rendering it at least difficult to bend the hook outward, and in the second place increasing its spring-power to retain the glasses, 20 and also giving a compound spring operating freely and easily both in the insertion and the removal of the glasses.

In the accompanying drawings, Figure 1 is 25 an isometrical elevation of the holder complete. Fig. 2 is a vertical longitudinal section. Fig. 3 is an isometrical elevation of a holder in which the hook-extension is bent outwardly from the hook. Fig. 4 is a like 30 elevation of a holder in which the hook-extension is bent inwardly from the hook and only extends part way to the eye.

A represents the back, provided with a pin and catch, 1, by which the holder is secured 35 to the clothing. The lower end of this back is bent, as at 2 and 3, and curving thence around and upward, as at 4 and 5, thereby forming a chamber within the bottom of the holder. From the bend 5 it extends upward, 40 and when the desired height is reached it is bent, as at 6, upon itself, and thence extends downward adjacent to the upward extension 7, as in Fig. 1. This downward extension 8 reaches down to the bottom of the holder and 45 enters the slot 9 therein, as shown by the sectional view.

When the eye frame or handle of the glass is inserted at the bend 6, and drawn downward between the back A and the downward extension 50 8, the resulting compression of this part 8 outward springs it, and this spring action is

transmitted through the bend 6 into the portion 7, and thence into the bend 4 and curve 5, as the handle or pin inserted eye descends, until it passes the bend 2, when the parts return to their normal position. 55

The point of part 8 is made to play back and forth in the slot 9, or between the curve 2 3 8, whenever the part 8 is sprung.

The eye-handle of the glass lies in the hook 60 or in the chamber at or near the bottom of the holder.

In all cases the hook proper is constructed of a piece of metal or other material doubled to form three or more bars, the parts of which 65 are capable of a compound spring action both when the eyeglass is inserted or removed; or when the hook catches in the clothing then this compound action prevents the hook from being easily bent outward; also, this action 70 prevents the eyeglass from slipping out or off from the hook accidentally.

In all of the figures I show the pin as formed by bending over backward an extension of the backs A. In fact, I show the whole holder as 75 constructed, stamped out, and bent to shape.

What I claim as my invention, and desire to secure by Letters Patent, is—

1. An eyeglass-holder consisting of a back piece bent to form an eye at its lower end and 80 provided with a pin and catch and a hook rising vertically from the eye and bent downward at the top to form a spring-extension to the hook, substantially as described.

2. The eyeglass-holder herein described, consisting of a back provided with pin and catch, 85 a hook and an eye integral with each other, and a downward extension of the hook substantially parallel with the back and hook, substantially as described. 90

3. In an eyeglass-holder, the combination of the eye connecting the back and hook and provided with a slot, 9, with the downward spring-extension of the hook, substantially as described. 95

In witness whereof I have hereunto set my hand this 30th day of September, 1886.

CALVIN S. BALL.

In presence of—

C. W. SMITH,
C. GARLICK.
